COMBINATION HYDRAULIC PUMP AND CHEMICAL PROPORTIONER FOR WATER TREATING SYSTEM OR SIMILAR ARTICLE

Nat Cordis, Crown Farm, Silver Lake, Wis.

Filed Aug. 6, 1962, Ser. No. 71,182

Term of patent 14 years

(Cl. D65—1)

Fig. 1

Fig. 2

*Fig. 3.**Fig. 4.*FIGURE 1 is a front elevational view of a combination hydraulic pump and chemical proportioner for water treating system or similar article showing my new design;

FIGURE 2 is an elevational view of the right side thereof;

FIGURE 3 is a top plan view thereof;

FIGURE 4 is an elevational view of the left side thereof; and

The undisclosed side corresponds to the side shown in FIGURE 1 except for the broken lines shown in FIGURES 2, 3 and 4.

The dominant features of the design are shown in full lines.

I claim:

The ornamental design for a combination hydraulic pump and chemical proportioner for water treating system or similar article, as shown and described.
